CLAIM

The ornamental design for an electronic relay programmer, as shown and described.

DESCRIPTION

FIG. 1 is a top perspective view of the electronic relay programmer according to the invention;

FIG. 2 is a top plan view of the programmer of FIG. 1; FIG. 3 is a left side view of the programmer of FIG. 1; FIG. 4 is a right side view of the programmer of FIG. 1;

FIG. 5 is a bottom view of the programmer of FIG. 1; and,

FIG. 6 is an end elevational view of the programmer of FIG. 1, the opposite end elevational view being a mirror image.

FIG. 1

FIG. 2

FIG. 3

FIG. 4

FIG. 5

FIG. 6
